Attorneys

UNITED STATES PATENT OFFICE.

HARRY W. YOUNG, OF WHITEHALL, MICHIGAN.

HAWSE-PIPE.

1,287,168.

Specification of Letters Patent. Patented Dec. 10, 1918.

Application filed April 30, 1917, Serial No. 165,471. Renewed April 27, 1918. Serial No. 231,279.

To all whom it may concern:

Be it known that I, HARRY W. YOUNG, a citizen of the United States, residing at Whitehall, in the county of Muskegon and State of Michigan, have invented new and useful Improvements in Hawse-Pipes, of which the following is a specification.

This invention relates to devices for lining opening in a vessel's bow, stern or sides to facilitate the passage of hawsers or cables therethrough, and its object is to provide a simple and cheap device of this kind which can be easily fitted to suit different kinds of vessels.

The object stated is attained by means of a novel combination and arrangement of parts to be hereinafter described and claimed; reference being had to the accompanying drawing forming a part of this specification.

20 In the drawing—

Figure 1 is a perspective view showing the application of the invention;

Fig. 2 is a longitudinal section thereof; and

25 Fig. 3 is a sectional view showing a slight modification.

Referring specifically to the drawing, 5 denotes the deck, and 6 one of the sides of a vessel. The invention is shown applied to 30 this part of the vessel, but it will be understood that it may also be applied to the bow, the stern or any other portion of the vessel from which a hawser or cable is to be run.

In the deck 5 is an opening 7, and the 35 side 6 has an opening 8, and between these openings extends a hawse pipe having flared ends seating in the openings. The hawse pipe is composed of two or more sections 9 having their adjacent ends coupled by a 40 sleeve 10, the pipe ends being oppositely threaded as shown in Fig. 2, so that they are drawn together when the sleeve is turned.

The flared ends of the pipe sections 9 are 45 separate therefrom and they are composed of the following parts:

Over the deck opening 7 is fitted and suitably secured a floor plate 11 having a tubular bottom extension 12 passing through the

opening and positioned obliquely so that it 50 projects downward and sidewise in the direction of the side opening 8. This extension is tapered, its widest portion being where it joins the floor plate. The upper pipe section 9 is connected to the lower end of the 55 extension, the upper end of this pipe section being enlarged slightly to partly spherical form, or flared, as shown at 13, and the lower end of the extension being shaped to fit around the same, whereby endwise separation of the parts is prevented.

Over the opening 8 is mounted a plate 14 having a tubular extension 15 passing inward through the opening and pointing upward so that its inner end may be connected 65 to the outer end of the lower pipe section 19, the connection being made in the same manner as the connection with the part 12.

The parts can be readily assembled, and the pipe sections are held in perfect alignment and tightly fitted to the parts 12 and 15 by drawing the sections together by means of the sleeve 10.

Fig. 3 shows the end of the pipe section 9 which is connected to the part 12 fitted 75 with a partly spherical retaining collar 16 as a substitute for the flared end 13. The other pipe section will be fitted with a similar collar for connection to the part 15.

I claim:

1. A hawse pipe having flared end sections composed of plates provided with tubular extensions, the ends of the pipe being flared for connection to the extensions, the outer ends of the extensions fitting 85 around said flared ends.

2. A hawse pipe having flared end sections composed of plates provided with tubular extensions, the ends of the pipe being flared for connection to the extensions, the outer ends 90 of the extensions fitting around said flared ends, the pipe being composed of aligned sections having their adjacent ends oppositely threaded, and a coupling sleeve mounted on said threaded ends of the pipe sections. 95

In testimony whereof I affix my signature.

HARRY W. YOUNG.
